(57) **CLAIM**

The ornamental design for a paint spray gun as shown and described.

DESCRIPTION

FIG. 1 is an upper perspective view of a paint spray gun showing our new design.

FIG. 2 is a front view thereof;

FIG. 3 is a side view of the paint spray gun, an opposite side view being a mirror image thereof;

FIG. 4 is a top view of the paint spray gun; and,

FIG. 5 is a rear view thereof.

1 Claim, 5 Drawing Sheets
